UNITED STATES PATENT OFFICE.

ERNEST HAYWARD FAIRBANKS, OF MERCHANTVILLE, NEW JERSEY.

DESIGN FOR A PHONOGRAPHIC-DISK-RECORD CABINET.

55,596.

Specification for Design.

Patented July 6, 1920.

Application filed May 14, 1920. Serial No. 381,477. Term of patent 14 years.

To all whom it may concern:

Be it known that I, ERNEST HAYWARD FAIRBANKS, a citizen of the United States, residing at Merchantville, in the county of Camden, State of New Jersey, have invented a new, original, and ornamental Design for Phonographic - Disk - Record Cabinets, of which the following is a specification, reference being had to the accompanying drawing, forming part thereof.

The figure is a perspective view of a pho-

nographic disk record cabinet, showing my new and ornamental design, wherein 1 designates the cabinet having the vertical, parallel, closely related, record holding compartments 2, the record ejectors 3, and the upwardly inclined record arresting device 4.

I claim:—

The ornamental design for a phonographic disk record cabinet, as shown.

ERNEST HAYWARD FAIRBANKS.
